UNITED STATES PATENT OFFICE.

WILLIAM L. MORRIS, OF CHICAGO, ILLINOIS, ASSIGNOR TO THE BOOTH ELECTRIC FURNACE CO., A CORPORATION OF ILLINOIS.

ELECTRODE-ADJUSTING MECHANISM.

1,386,017.

Specification of Letters-Patent.

Patented Aug. 2, 1921.

Application filed April 19, 1920. Serial No. 374,966.

To all whom it may concern:

Be it known that I, WILLIAM L. MORRIS, a citizen of the United States, residing at Chicago, in the county of Cook and State of Illinois, have invented a new and useful Improvement in Electrode-Adjusting Mechanism, of which the following is a specification.

This invention relates particularly to electrode-holders for electric furnaces. The improved device is especially useful in connection with electric furnaces employing substantially horizontal electrodes.

The primary object is to provide improved electrode holding and adjusting means, adapted to secure proper alinement and enable easy adjustment of the electrodes.

The invention is illustrated in the preferred embodiment in the accompanying drawings in which—

Figure 1 represents a broken vertical sectional view of an electric furnace embodying the invention in its preferred form; Fig. 2, a sectional view taken as indicated at line 2 of Fig. 1; Fig. 3, a sectional view taken as indicated at line 3 of Fig. 2; Fig. 4, a sectional view taken as indicated at line 4 of Fig. 2; Figs. 5 and 6 are views taken as indicated at the corresponding lines of Fig. 3; Fig. 7, a detailed sectional view taken as indicated at line 7 of Fig. 3; Fig. 8, a view corresponding with Fig. 2, but illustrating a modification of the invention; Fig. 9, a sectional view taken as indicated at line 9 of Fig. 8; and Fig. 10, a view taken as indicated at line 10 of Fig. 8.

In the construction illustrated in Figs. 1 to 7, inclusive, A represents a furnace-body of the type which is adapted to rotate or oscillate about a horizontal axis, the body being usually supported on rollers (not shown) and actuated by means of mechanism A'; B, an electrode supporting-frame projecting from the end of the furnace-body; C, C', axially disposed electrodes which extend through the end walls of the furnace; and D, an electrode clamp mounted on the frame B.

It will be understood that the furnace is equipped at each end with an electrode supporting-frame, and with the clamp D adjustably mounted thereon. The furnace-body A may be of any suitable construction and may be mounted to rotate or oscillate, if desired. The furnace-body is provided near its ends with insulated annular tracks

A² (one shown) which are energized by brushes or stationary contact members 1 (one shown). These annular tracks are connected with the electrode clamps D as by means of flexible conductors 2, shown in Figs. 2 and 3, and diagrammatically indicated in Fig. 1. The circuit is completed through the electrodes, the furnace operating through an arc 3, if desired.

The electrode supporting-frame B comprises an adjustable mounting 4 carried by the end wall of the furnace; an outer plate 5; end guides 6 interposed between and secured to said plates. Any suitable construction for the electrode supporting-frame may be employed, however. The electrode clamp D, in the illustration given, comprises a crescent-shaped slide 7 mounted on the guides 6, the member 7 being provided at its lower portion with an extension 7^a which constitutes a supporting bracket for the electrode clamp proper; a lower stationary jaw or clamping-member 8 adjustably mounted on the arm 7^a in such manner as to permit the electrode to be adjusted to a correct axial position, an upper electrode clamping-member 9, connected by means of a pivot 10 with the clamping-member 8; and a right and left threaded screw-rod 11 equipped with a handle 11^a and serving to adjust the clamping members 8 and 9.

In the illustration given, the carriage or slide 7 is actuated by means of screw-rods 12 whose reduced end portions are journaled in the frame-members 4 and 5, so that the screws will not move longitudinally. The slide 7 is provided with vertical bores in which are journaled plugs or bearing members 13 having transverse threaded perforations which engage the threads of the screw-rods 12. The members 13 preferably constitute steel or brass inserts in the casting forming the slide 7. The plug 13 is mounted in a vertical boss 14, and the screw-rod 12 extends through a horizontal boss 15 which forms a cross with the boss 14. The carriage or slide 7 may be moved towards or away from the end of the furnace by actuating the screw-rods 12. These rods may be actuated in any suitable manner. Preferably this is accomplished by equipping the outer end of the screw-rods with pinions 17 which are engaged by a gear 18 formed integrally with a hand-wheel 19 which is journaled in the outer frame-member 5. The

hand-wheel is tubular, so that the electrode can work freely through it; and the gear 18 is formed integrally with the hand-wheel.

The arm 7^a of the slide 7 is in the form 5 of a short horizontal bar occupying a vertical plane. The clamping-jaw 8 has a T-form shank which provides a horizontal bar 8^a occupying a vertical plane and a horizontal bar 8^b occupying a horizontal plane. 10 Interposed between the arm 7^a and the shank 8^a is a bearing block 20 of cylindrical form, which has encircled end surfaces 20^a which bear against similarly curved concave surfaces with which the adjacent side-members 15 7^a and 8^a are provided. The members 7^a and 8^a are connected by four bolts 21 disposed at the corners of a rectangle and outside the circumference of the spacing-member 20. Thus, the jaw 8 is capable of a 20 sort of universal adjustment on the arm 7^a of the slide or carriage to vary the plane of the electrode clamping-members 8 and 9 and thus vary the tilt of the axis of the bore 25 between the jaws with respect to the line of movement of the carriage when it is adjusted through the medium of the screw-rods 12. The adjustment of the jaws on the carriage may be effected by releasing some of the bolts and tightening others, as may 30 be necessary, to enable the electrode to be brought into proper axial position with respect to the furnace.

The jaws 8 and 9 are provided near their pivot points with short arms 22 which are 35 connected with the conductors 2 by means of bolts 23. The supporting jaw 8 is insulated from the carriage by bushings 23 and a disk 24, as shown in Fig. 5. Thus, the electric current is led directly to the jaws, 40 and the jaws are insulated with respect to the carriage. The clamping-members 8 and 9 are provided at their free ends with lugs 25 in which are journaled horizontal bearings 26 which are provided with transverse 45 threaded portions engaged by the right and left threads of the screw-rod 11. The members 26 can turn on their axes, as may be necessary, in opening and closing the jaws. This will be readily understood from Figs. 50 4 and 7.

In the modification shown in Figs. 8 to 10, inclusive, the slide or carriage is in the form of a ring 7^b, mounted on the guide-rod 6 of the electrode supporting-frame and actuated by the screw-rods 12, in the manner described above. In the ring 6 is supported an inner ring 27 of channel-form 55 cross-section, separated from the encircling ring 6 by insulation blocks 28. Within the ring 27 and separated therefrom by insulation 60 29 is another ring 30 having flanges 30^a and 30^b, one of which is removable. The ring 27 and insulation 29 are interposed between the flanges 30^a and 30^b, and the parts 65 are clamped together by transverse bolts 31,

suitable insulation being provided, as shown in Fig. 10. Thus, the ring 30 is insulated from the annular carriage. The electrode clamping-jaws 32 are spaced within the ring 30 and are carried by right and left screw-rods 33 which connect the end portions of the jaws with lugs 34 with which the ring is provided at its sides. The jaws are bonded to the ring 30 by flexible copper bars 35. Thus, it will be understood that the tilt of 75 the jaws may be varied to vary the tilt of the electrode and bring it into proper axial position with respect to the furnace.

Connected with the ring 30 is a flexible copper bar 36, which corresponds with the 80 conductor 2 of the construction shown in Fig. 1.

Referring to Fig. 1, 37 represents a water-cooled bearing in the end wall of the furnace. This connects with a system of water-cooling pipes 38, which need not be described in detail.

From the description given, it will be understood that each of the constructions described provides a carriage or slide which is 90 adjustable toward and away from the furnace, and electrode clamping means mounted thereon and provided with means for varying the tilt of the electrode and bringing it into proper axial position with respect to the furnace. In the first described construction, the electrode clamping-members are simultaneously adjusted to vary the tilt. This is the preferred construction. 95 However, the desired result may be secured 100 by any suitable construction.

The foregoing detailed description has been given for clearness of understanding only, and no unnecessary limitations should be understood therefrom, but the appended 105 claims should be construed as broadly as permissible in view of the prior art.

What I regard as new and desire to secure by Letters Patent is—

1. In means of the character set forth, the 110 combination of an electrode supporting-frame, a carriage adjustably mounted for movement longitudinally of said frame, and electrode clamping means mounted on said carriage and provided with means of adjustment to vary the axial direction of the electrode.

2. In means of the character set forth, the 115 combination of an electrode supporting-frame, an adjustable carriage mounted thereon, electrode clamping-means, and means for varying the angle of the axis of the bore of the clamping-jaws of said clamping-means with respect to the line of movement of said carriage.

3. In means of the character set forth, the 120 combination of an electrode supporting-frame, a carriage adjustably mounted for movement longitudinally of said frame, and electrode clamping means insulatingly 125

mounted on said carriage and provided with means of adjustment to vary the axial direction of the electrode.

4. In means of the character set forth, the combination of an electrode supporting-frame, a carriage adjustably mounted for movement longitudinally of said frame, and a plurality of electrode clamping-jaws, and adjustable means for mounting the same on 10 said carriage whereby said jaws may be simultaneously adjusted to vary the axial position of the electrode.

5. In means of the character set forth, the combination of an electrode supporting-frame, a carriage adjustably mounted for movement longitudinally of said frame, a pair of pivotally connected clamping-jaws, and mounting means carried by said carriage and supporting said jaws, said mounting means being provided with means of adjustment for varying the position of an electrode carried by said jaws.

6. In means of the character set forth, the combination of an electrode supporting-frame, a carriage adjustably mounted thereon for movement longitudinally of said frame, said carriage being provided with a jaw-supporting member, a jaw adjustably secured on said jaw-supporting member, a 25 jaw pivotally connected with said first-named jaw, and means for clamping said jaws together.

7. In means of the character set forth, the combination of an electrode supporting-

frame, a crescent-shaped carriage mounted 35 thereon, means for moving said carriage longitudinally of said frame, an arm projecting from one end of the crescent-shaped carriage, an electrode clamping-jaw adjustably secured on said arm, a companion jaw 40 pivotally connected with said first-named jaw, and means for clamping said jaws upon an electrode.

8. In means of the character set forth, the combination of an electrode supporting-frame, a carriage adjustably mounted for movement longitudinally of said frame, said carriage being provided with a jaw-supporting member, an electrode clamping-jaw insulatingly and adjustably mounted on said 45 jaw-supporting member, a companion electrode clamping-jaw mounted on the first mentioned jaw, and means for clamping said jaws upon an electrode.

9. In means of the character set forth, the combination of an electrode supporting-frame, a carriage adjustably mounted for movement longitudinally of said frame, said carriage being provided with a bar-like arm occupying a vertical plane, an electrode 50 clamping-jaw having a bar-like shank spaced with relation to said arm, a bearing member interposed between said shank and said arm, bolts connecting said shank and arm, a clamping-jaw mounted on said first-named jaw, and means for clamping said 55 jaws upon an electrode.

WILLIAM L. MORRIS.
